UNITED STATES PATENT OFFICE.

JOHN EDGAR OSMER, OF CLINTON, IOWA.

SAFETY-VALVE.

SPECIFICATION forming part of Letters Patent No. 666,109, dated January 15, 1901.

Application filed July 20, 1900. Serial No. 24,311. (No model.)

To all whom it may concern:

Be it known that I, JOHN EDGAR OSMER, a citizen of the United States, residing at Clinton, in the county of Clinton and State of Iowa, have invented certain new and useful Improvements in Safety-Valves; and I do declare the following to be a full, clear, and exact description of the invention, such as will enable others skilled in the art to which it applies to make and use the same.

My invention relates to improvements in safety-valves for use on steam-boilers, and has for its object to provide a safety pop-valve which is simple of construction, balanced in an effective manner to secure the requisite degree of sensitiveness without chattering, and adapted to relieve the excess pressure on the boiler quickly and promptly and without the loud and prolonged noise produced by safety-valves of ordinary construction.

With this and other minor objects in view the invention consists of certain novel features of construction, combination, and arrangement of parts, as will be hereinafter more fully described, and particularly pointed out in the appended claims.

In the drawings hereto annexed and forming a part of this specification, Figure 1 is a side elevational view of a safety-valve constructed in accordance with my invention. Fig. 2 is a top plan view of the same. Fig. 3 is a vertical longitudinal section showing the parts of the valve in their normal or closed positions. Fig. 4 is a similar view showing the valves open to equalize the pressure and exhaust the excess steam. Fig. 5 is a sectional view on line 5 5 of Fig. 3. Fig. 6 is a perspective view of the internal cylinder, duplex valves, and coöperating parts. Fig. 7 is a similar view of the pressure-spring and coacting parts.

Referring now more particularly to the drawings, in which like reference characters designate corresponding parts throughout the several views, the numeral 1 represents the cylindrical valve-casing, comprising a base or main section 2 and a dome or cap section 3, said base-section being formed or provided at its outer end with an internally-threaded extension 4 for connection with a steam-escape pipe leading from the boiler and at its inner end with an annular shoulder or enlargement 5, formed with a valve-seat 6 and

external threads to receive the threaded inner or lower end of said dome-section 3, whereby the sections are coupled together. The dome-section is provided with a hexagonal head 7 for application of a wrench or analogous tool thereto in applying and removing it, two annular series of escape-ports 8 and 9, 60 one opening to the atmosphere through said head and the other through the top of the dome at the base of the head, and a central screw-threaded opening 10, in which works an adjusting-screw 11, held in fixed position by 65 a lock-nut 12. This screw is provided with a rectangular outer head 13, to which a wrench may be applied for adjusting it, and a tapered or hemispherical inner end 14, designed for a purpose hereinafter set forth. The base-section 2 has arranged therein a guide-chamber 15, provided at its upper open end with a valve-seat 16. This guide-chamber, in conjunction with webs 17, which support it, divides the interior of the base-section into a 75 lower steam-inlet chamber 18 and upper balancing-chamber 19, said chambers being in communication through ports or passages 20, formed by the spaces between said webs. The guide-chamber and webs are preferably cast 80 integrally with the said base-section 2. The interior of the dome-section 3 forms an equalizing-chamber 21, into which the excess steam passes before exhausting to the atmosphere.

Mounted to slide vertically in the casing is 85 a duplex valve device comprising an internal cylinder or hollow carrier 22, open at each end and fitted to slide at its upper end in an annular guide 23, projecting from the under side of the top of the dome. This cylinder 90 or carrier has formed therewith or attached thereto two valves 24 and 25 of different areas, the upper and larger valve 24 being designed to rest upon the seat 6 and the smaller and lower valve 25 upon the seat 16, and is provided above said upper valve 24 with a series of equalizing-ports 26, communicating with the said equalizing-chamber 21. A hollow extension or spider 27 hangs pendent from the under side of the lower valve 25 and is 100 attached thereto by an annular web or flange 28 of less thickness than the valve and extension 27 and forming an annular steam-inlet space 29. With this space communicate a series of vertical regulating-ports 30, extending through the piston and opening into

the guide-chamber 15. The extension 27 is mounted to slide vertically within the guide-chamber, and the latter is in communication through said extension 27 with the internal 5 cylinder or valve-carrier 22. Instead of employing an extension of the construction shown I may employ a spider in which the ports 30 are formed by the spaces between the arms of the spider, as will be readily understood.

The valves 24 and 25 are normally held closed against their seats 6 and 16 by a coiled or a spiral pressure-spring 31, bearing at its lower end against a flanged washer 32, bearing 15 upon a shoulder 33 at the base of the internal cylinder or carrier 22 and at its upper end against a flanged cap 34, provided with ports 35 for the passage of steam from said cylinder to the escape-ports 8. This spring 20 serves as a common tension device to hold the valves 24 and 25 seated and the extension 27 down to its lowermost position in the dash-pot 15, in which position the ports 30 are out of communication with the balancing-chamber 19, with which the dash-pot communicates 25 when the valve 25 is open. The tapered or hemispherical end 14 of the adjusting-screw 11 turns within a seat or depression 36, formed in the cap 34, and by turning this screw in 30 one direction or the other the tension of the spring may be regulated to adapt the valves to open at any pressure desired.

The operation of the valve is as follows: The normal position of the ports when the 35 steam in the boiler and chamber 19 is at or below safety-pressure is shown in Fig. 2. When the pressure in the balancing-chamber 19 is sufficient to overcome the tension of the spring, the carrier 22, valves 24 and 25, and 40 extension 27 rise, thereby bringing the chamber 19 into communication with the equalizing-chamber 21 and guide-chamber 15, and the steam passes upward and out to the atmosphere through the ports 9 and also down 45 through the ports 30 into the guide-chamber 15, thence upward through the internal cylinder or valve-carrier 22, and out to the atmosphere through the ports 35 and 8. Owing to the fact that the valve 25 is of less area— 50 that is, has less surface exposed—than the valve 24 the steam within the balancing-chamber 19 presses upon the upper surface of the valve 25 with somewhat less force than upon the under side of valve 24. Hence the 55 valves are prevented from opening with violence and from chattering and are balanced in a simple and effective manner. At the point of popping or blowing off if the volume of the steam is not of great force the valves will 60 open to allow the excess steam to pass out and then immediately seat, for the reason that the regulating-ports 30 will discharge the steam from the under side of valve 25 and prevent an upward pressure thereon; but if 65 the pressure comes with great force or volume and the steam cannot pass downward through the ports 30 fast enough it will exert an up-

ward pressure on the under side of valve 25, which adds the area of said valve 25 to that of the valve 24, and in consequence the valves 70 will rise to a greater extent and discharge a much greater volume of steam to the atmosphere. The relative areas of the valves 24 25 are therefore of great importance in order to secure an effective sensitive balancing action 75 and prevent extreme sensitiveness and chattering of the valves and the discharge of too much steam. The ports may be so proportioned that the steam-gage employed on the boiler will indicate the opening and closing 80 of the valves at the same point of pressure.

The construction of the valve herein shown and described is deemed preferable; but it will of course be understood that modifications within the scope of the invention as defined by the appended claims may be made without departing from the spirit thereof.

Having thus fully described my invention, what I claim as new and useful, and desire to secure by Letters Patent of the United States, 90 is—

1. In a double-seated safety-valve for steam-boilers, the combination of a valve-casing comprising separable base and dome sections and having an inlet-port in its bottom, two sets of discharge-ports in its top, a lower-valve guide having a valve-seat, an upper-valve guide between the said sets of discharge-ports, and a valve-seat between said guides, together with a hollow valve device inclosed within said 100 casing and having valve members coöperating with said seats and forming upper and lower chambers, inlet-ports opened and closed by the lower-valve member and establishing communication between the interior of the 105 valve and said lower chamber, equalizing-ports establishing communication between the interior of the valve and said upper chamber, and a pressure-spring inclosed within the 110 valve and adapted to hold said valve members to their seats, substantially as set forth.

2. In a double-seated safety-valve for steam-boilers, the combination of a casing having an inlet-port in its bottom, two sets of discharge-ports in its top, a lower-valve guide 115 having a valve-seat, an upper-valve guide between the said sets of discharge-ports, and a valve-seat between said guides, and a hollow valve device having valve members coöperating with said seats, an internal shoulder, a relief-ports above the upper-valve member, a coiled pressure-spring on the interior of the 120 valve device and bearing at its lower end on said shoulder, a perforated cap bearing upon the upper end of the spring, and an adjusting 125 device acting on said cap, substantially as set forth.

In testimony whereof I have hereunto set my hand in presence of two subscribing witnesses.

JNO. EDGAR OSMER.
